UNITED STATES PATENT OFFICE.

GEORGE W. DAVIS, OF HOT SPRINGS, ARKANSAS.

TRACK-SCRAPER FOR STREET-RAILWAYS.

SPECIFICATION forming part of Letters Patent No. 378,292, dated February 21, 1888.

Application filed November 23, 1887. Serial No. 256,021. (No model.)

To all whom it may concern:

Be it known that I, GEORGE W. DAVIS, a citizen of the United States, residing at Hot Springs, in the county of Garland and State of Arkansas, have invented a new and useful Improvement in Scrapers and Steel Brushes for Street-Railways, of which the following is a specification.

This invention relates to the class of track-cleaners that are carried on the passenger-cars of street-railways, the object being to construct at a reasonable cost a cleaner that shall be reliable in action and simple in detail, and one that shall be easy of operation.

I am aware that it is old to clean tracks by means of scrapers and brushes, and do not, therefore, broadly claim such devices as my invention.

It consists, therefore, of means whereby scraping-blades are operated and attached, and in the peculiar shape of said blades, in brushes made of stiff material of sufficient stiffness to break up and render more easily removable the ice, snow, or other obstruction desired removed, and other details, all of which will be hereinafter fully set forth, and the parts thought to be new pointed out in the claims.

In the accompanying drawings, Figure 1 is a side view of my device, partly in section, showing the details of one end of a car, both ends being duplicates. Means for ventilating the car are also shown in this figure. Fig. 2 is a side view of the car, further showing the device. In this figure the pulverizing-brush is shown only on the left-hand end of its shaft, the corresponding one on the other end of the shaft being removed to show the conformation of the bottom edge of the scraper to the track, as hereinafter fully described. Fig. 3 is a top view, further showing the form of the scraper.

In the figures, like reference-marks indicating corresponding parts in the several views, A are the scrapers, which are best shown in Figs. 1 and 3, the latter figure being a detail. The scrapers are preferably of about the form shown, and have a bottom edge of such a conformation as to fit nearly in shape to the top of the rail; of whatever kind it may be, and extend toward the center of the track a sufficient distance to clear a space for the passage of the flange of the wheel. It is necessary that the shape of the bottom edge of the scrap-

er-blades should conform to the top of the rail, as it will then leave nothing on the top of said rail after its passage, and, as above stated, it may conform to any kind of rail without a departure from the spirit of my invention. These scrapers are carried on the free ends of the spring-levers B, said levers being pivoted on the pins or screws b between the head and the pin b'. These spring-levers B may be made to spring throughout their entire length, or they may only spring for a part of their length, as in either case an elastic contact with the track would be accomplished, which is necessary in order that the scrapers may not catch on any irremovable obstacle—as, for instance, the end of a rail which has sprung up. I do not, however, confine myself to the specific manner of pivoting shown, as many other ways would suffice. I prefer the pivoting of the levers B, as shown, by means of the screw b, having the pin b', inasmuch as by means of this screw b the lever, and hence the scrapers and pulverizer, may be adjusted in height from the track, and in localities where it is not necessary to use this device continuously it may be readily removed, and replaced when again required.

Near the point of attachment of the scrapers A are the brackets or extensions c from the levers B, for the purpose of carrying the shaft of the pulverizing wheels or brushes C. These pulverizers are made in the form of a very stiff brush, having teeth projecting from a central core of wood or metal and of a sufficient stiffness to pulverize and prepare the ice, hard snow, and other obstruction for ready removal by the scraper-blades A. The shaft D, which carries the pulverizers and is itself carried by the arms c, has a sprocket-wheel, d, which is driven by a belt from the sprocket-wheel d' on the axle that is nearest the end of the car on which this device is shown. On the axle and engaging with the sprocket-wheel d' is a clutch, d'', for the purpose, by its engagement and disengagement, of starting and stopping the pulverizers C, the clutch being capable of movement longitudinally and revolving positively with the shaft.

At times when the scrapers and pulverizers are not needed, and consequently the sprocket-wheel d' would be otherwise superfluous, the belt a may be made slightly longer and extended to a sprocket-wheel on the shaft e, for

the purpose of driving the fan F. This fan F is for the purpose of ventilating the car, and may be run in any direction, but is preferably run in such direction that the fan in the front 5 end of the car will take in air and force it into the car, and the one in the rear running in an opposite direction will take it out of the car, which establishes a current of air that is nearly free from dust. Screens of sufficient fine- 10 ness to obstruct the dust may be placed over the openings shown directly under the fan in Fig. 1. The air of course may be distributed through the car in any approved manner. The rotary motion may be transmitted from the 15 shaft e to the fan F by means of the miter-gearing f. The fan will only be necessary when the scrapers and pulverizers are not in use; hence only one sprocket-wheel is required on the car-axle, although simply by the addition 20 of a second sprocket on the axle both might be run at the same time.

The levers B, hinged on the screw b or otherwise, have at the end opposite the place of attachment of the scrapers A and pulverizers 25 C means of attachment of a hand or foot bar, E, as shown. On the platform is the catch e, for engagement with the bar E, when up, for the purpose of keeping the front ends of the levers pressed down, and hence the scrapers

and pulverizers up and out of contact with the track, in which position they will of course cease to perform their functions. The screws b may be turned in or out, as required, to adjust the height of the pulverizers and scrapers to make up for any variations that might occur in the height of the car from the track in consequence of the settling of the springs or for other reason.

Having thus described my invention, what I claim as new, and desire to secure by Letters Patent of the United States, is—

1. In a street-car, a track-cleaning device consisting of the scrapers A and the pulverizers C, carried on the frame of the car, the pulverizers being revolved by belt-connection 45 with the axle of the car, substantially as shown and described, and for the purpose specified.

2. In a street-car, a track-cleaning device consisting of the levers B, the scrapers A, the adjustable pivoting-screw b, the toothed actuating-bar E, and the pawl e, all combined and operating substantially as described.

Given under my hand this the 24th day of August, 1886.

GEO. W. DAVIS.
